UNITED STATES PATENT OFFICE.

EWALD F. TOBOLD, OF CLEVELAND, OHIO, ASSIGNOR TO THE DILL MANUFACTURING COMPANY, A CORPORATION OF OHIO.

VALVE-ASSEMBLING MACHINE.

Application filed March 23, 1925. Serial No. 17,675.

This invention relates to a valve assembling machine which is designed to insert the packing into a valve member, the machine herein shown being employed for inserting the rubber packing into valve members such as those attached to the inner end of the valve pins of the check valves which are mounted within the outer ends of the valve stems of pneumatic tires.

10 An object of the present invention is to provide a continuous operated automatic machine for rapidly applying the packing to valve members of the type above referred to.

15 A further object is to insure a perfect fit between the packing and valve member by employing each valve member itself as a die for cutting its own packing from a strip of packing material.

20 A further object is to provide means for perforating the packing after it has been inserted into the valve member and for freeing the packing and valve member from the perforating die without loosening the packing or dislodging the same from the valve member.

With the above and other objects in view the invention may be said to comprise the machine as illustrated in the accompanying drawings hereinafter described and particularly set forth in the appended claims, together with such variations and modifications thereof as will be apparent to those skilled in the art to which the invention appertains.

Reference should be had to the accompanying drawings forming a part of this specification in which Fig. 1 is a side elevation of the machine; Fig. 2 is a horizontal section taken below the movable head of the press and showing in plan view the mechanism mounted on the bed of the press; Fig. 3 is a central longitudinal section showing a portion of the movable head of the press in side elevation; Fig. 4 is a broken sectional elevation showing in transverse section, a portion of the bed and carrier at the point where the packing is inserted into the valve member, the major portion of the movable head of the press being omitted to show the blank feeder mechanism in elevation; Fig. 5 is a fragmentary detailed view showing the mechanism by which the reciprocating packing strip feeder is actuated from the movable head of the press; Fig. 6 is a de-

tailed view showing the oscillating discharge chute and wiper in side elevation; Fig. 7 is a fragmentary bottom plan view of the discharge end of the blank feed chute; Fig. 8 is a section taken on line 8-8 of Fig. 3; 60 Fig. 9 is a plan view of the carrier actuating arm; Fig. 10 is a side elevation of the arm shown in Fig. 8; Fig. 11 is a detailed view showing the carrier latch and pivoted trip member in side elevation; Fig. 12 is a top 65 plan view of the latch trip member; Fig. 13 is a side elevation of the vertically swinging feeder which delivers the blanks from the supply hopper to the feed chute; Fig. 14 is a top plan view of the feeder shown in Fig. 70 13; Fig. 15 is an axial section through the cup-shaped metallic portion of one of the valve members; Fig. 16 is a view similar to Fig. 15 showing the valve member with the packing therein. 75

In the present invention as illustrated in the accompanying drawings the principal operations are performed by a mechanism carried by parts of a bench press of well known construction in which there is a stationary bed 1 and a reciprocating head 2 movable toward and from the bed, the head being actuated by a connecting rod 3 extending from a crank shaft 4 which is continuously driven in any manner and serves to reciprocate the head at the desired rate, parts of the rod 3 and crank shaft 4 being shown in Fig. 1 of the drawing. A rotary carrier 5 is mounted upon a fixed vertical stub-shaft 6 secured to the bed centrally thereof and the carrier or table 5 is provided adjacent the periphery with regularly spaced pockets 7, each of which is adapted to receive one of the valve members and which serves to support a valve member while the various operations are being performed thereon. The valve members are delivered to the rotary carrier from a supply hopper 8 through a feed chute 9 in such manner as to supply one valve member to each pocket of the carrier as the same is rotated, the valve members being discharged after the various operations are completed through a discharge chute 10 secured to the base at the side of the carrier opposite that at which the feed chute is located. Fig. 15 of the drawings shows a metallic shell or blank 11 into which the packing is inserted by the machine. This blank has an enlarged end 12 which is provided with a recess 13 to receive the packing, and below the recess 13 110

the member 11 is provided with an axial bore 14 to receive the valve pin. As shown in Fig. 1 of the drawing, the supply hopper 8 which is adapted to contain a suitable quantity of the blanks 11 is provided with a vertically movable oscillatory feed arm 15 which is mounted to swing upon a horizontal pivot 16 at the forward end of the hopper, and carries a vertically disposed segment plate 17 which projects through a slot in the bottom of the hopper, and has its ends 18 and 19 cut upon arcs of concentric circles having their center at the pivotal axis of the arm 15, so that the plate 17 while moving vertically in the slot in the bottom of the hopper, closes said slot in all of its positions. The plate 17 is provided with a groove 20 along its upper edge, which has a cross-sectional shape corresponding to an axial section through a blank to be fed. The segment plate 17 in the movements of its carrying arm 15, moves from a position in which its upper edge lies along the bottom of the hopper 8, to a position in which said upper edge aligns with the feed chute 9. The feed chute 9 is provided with a groove 21, which is of the same shape as the groove 20 in the upper edge of the segment plate 17, so that when the upper edge of the segment plate is aligned with the chute, any blanks which are resting in the groove of the segment plate may slide into the groove 21 of the feed chute. The arm 15 projects inwardly beyond its pivot 16, and to its inner end is attached a vertical actuating rod 22 which carries a roller 23 which engages the under side of a cam 24 fixed to a cam-shaft 25 mounted in a fixed support above the hopper. The upper end of the rod 22 is provided with a guide slot 26 through which the cam-shaft 25 extends, the rod 22 being retained on the cam-shaft by a suitable retaining washer 27 on the cam-shaft. The cam-shaft 25 has fixed thereto a belt pulley 28, over which runs a belt 29 which extends from a pulley 30 secured upon the crank-shaft 4.

As the segment plate 17 is moved from its lowermost position through the loose mass of blanks 11 in the hopper 8, some of these blanks will drop into the groove 23 and assume a position therein, in which the upper enlarged portion 12 fits in the upper enlarged portion of the groove, and the smaller lower end portion of the blank extends into the narrower lower portion of the groove, such blanks being supported with their large ends uppermost. As the plate 17 approaches its uppermost position, its upper edge will be inclined at an angle such that any blanks resting upon the top of the plate, but not properly positioned in the groove will roll off the plate and drop back into the hopper. The cam 24 is so shaped that the plate 17 will have a dwell in its uppermost position in alignment with the chute 9 sufficient to permit

a number of blanks to slide from the groove 20 of the plate 17 into the groove 21 of the chute 9, so that the chute 9 is at all times substantially filled with blanks 11, all supported with their enlarged open ends uppermost. 70

The feed chute 9 has a discharge portion 31 which is horizontally disposed directly over and adjacent the top of the rotary carrier or table 5, and directly over the pockets 7 of the carrier the chute is provided with a discharge aperture 32 through which the blanks may pass one at a time into the pockets of the carrier. A feeding device is provided for feeding a blank from the chute into each pocket of the carrier, and the end-most blank in the chute is normally held against falling through the aperture 32 by means of a U-shaped retaining spring 33, the legs of which extend along opposite sides of the aperture and receive between them the lower small end of the blank. The discharge end of the chute has a cover-plate 34 provided with an aperture 34^a which registers with the discharge aperture 32, and the blanks are discharged from the chute into the into the pockets 7 by a yieldingly supported punch 35 carried by the movable head 2 of the press. The carrier 5 is indexed during each upward stroke of the head 2 of the press to bring an empty pocket 7 directly beneath the discharge aperture 32 of the chute, and upon downward movement of the head the punch 35 moves downwardly through the aperture 34^a into engagement with the end-most blank supported upon the legs of the spring 33, forcing the blank down into the pocket of the carrier. The punch 35 is slidably mounted in a casing 36 fixed to the under side of the head 2, and has at its upper end a head 37 which is engaged by a compression spring 38 interposed between the head 37 and the bottom of the press head 2. The punch 35 is thus yieldably supported so that the mechanism will not be damaged should a blank become jammed in the discharge end of the chute. 100

Each of the pocket 7 of the carrier is provided with an insert 39 which has a central bore 40 to receive the lower ends of the blanks 11, and a counter-bore 41 in which the enlarged packing receiving ends 12 of the blanks fit, the insert 39 forming a rigid support for the blanks. The carrier or table 5 is provided beneath each of the pockets 7 with an opening 42 through which portions punched out of the packing may be discharged. 115

Means is provided for insuring a continuous flow of blanks through the feed chute 9, and to this end a vibrator plate 43 is secured to one side of the chute by bolts 44, the plate 43 having a limited sliding movement on the bolts permitted by elongated slots 45 in the plate through which the bolts 125 130

44 extend. An angle plate 46 is secured to the plate 43 and has a flange closely overlying the groove 21 of the chute. A rapid vibratory movement is imparted to the plate 43, and the plate 46 carried thereby, through a vibrator pawl 47, adjustably secured to the plate by securing bolts 48 extending into the plate 43 through elongated slots 49 in the pawl. The pawl 47 has a pointed end engaging with a vertical serrated vibrator cam 50 fixed to the under side of the head 2 of the press. A spring 51 is connected at one end to the plate 43 and at its opposite end to a fixed support, and acts to move the plate 43 toward the press and to hold the pawl 47 in engagement with the cam 50. During the upward and downward movements of the head 2 of the press a rapid vibratory motion will be imparted to the plate 43, and the plate 46 carried thereby to insure continuous feed of blanks through the chute. The plate 46 extends to adjacent the receiving end of the chute 9 and prevents entry of any blanks thereto except those which are properly positioned in the slot 20 of the feed plate.

The intermittent indexing movement of the carrier 5 is imparted by an oscillating actuating arm 52 which is pivoted on the vertical shaft 6 of the carrier, the oscillating movement being imparted to the arm 52 from the reciprocating head 2 of the press through a connecting rod 53 which is connected by a vertical pivot 54 to the arm 52, and by a horizontal pivot 55 to a bell-crank 56 carried by a horizontal shaft 57 supported on the bed 1 and connected by a link 58 to the head. By the connections above described, the arm 52 is moved in one direction upon downward movement of the head to the press, and in the opposite direction upon upward movement of the head. The periphery of the carrier table 5 is provided with pawl-receiving notches 59 which have an angular spacing corresponding to the spacing of the pockets 7 of the carrier, and between the pawl-receiving notches 59 are latch-receiving notches 60 which are engaged by suitable locking means on the bed 1 to positively hold the carrier against movement during the intervals between actuations thereof. A pawl 61 is carried by a vertical pivot 62 at the outer end of the arm 52, the pawl 61 being supported in the plane of the table 5 beyond the periphery thereof, in position to engage with the notches 59, and being held normally in engagement with the periphery of the table by a spring 63 connected at one end to the outer end of the pawl, and at its opposite end to the arm 52. The arm 52 has an angular movement greater than that imparted to the table, and to prevent the pawl 61 from engaging in the intermediate notches 60 at the beginning of its actuating stroke, a blocking plate 64 is

provided, said plate being fixed to the bed and positioned to be engaged by the point of the pawl 61 when the arm 52 is at the end of its idle stroke.

For locking the table 5 against movement while disengaged from the actuating arm 52, a latch 65 is slidably mounted in a suitable guide 66 secured to the bed 1, and is pressed toward the carrier by a compression spring 67. Means are provided for automatically disengaging the latch 65 from the notch 60 in which it is engaged upon the beginning of the active stroke of the actuating arm 52, the arm 52 and the latch 65 having coacting trip members which serve to release the latch. The latch 65 has a trip member 68 which lies upon the top thereof, and is connected at its rear end to the latch 65 by a horizontal pivot 69, and is normally held against upward movement away from the latch 65 by a suitable spring 70. The latch 65 lies in the plane of the table 5, and the top surface thereof is in substantially the same plane as the top surface of the table, so that the trip member 68 is supported above the plane of the top of the table. When the latch 65 is in engaging position, the inner free end of the trip member 68 overlies the edge portion of the table 5, and is provided at its inner end with an under-cut inclined portion 71 on one side, and a beveled vertical face 72 on the other side. The actuating arm 52 has a trip extension 73 which is provided on one side with a beveled lifting edge 74 which engages with the inclined under-cut portion 71 of the trip member 68, and with an angularly disposed vertical face 75 which engages with the beveled face 72 of the trip member 68.

Fig. 2 of the drawing shows the actuating arm 52 in the position which it occupies at the completion of the down stroke of the press head 2. As the press head moves upwardly, the actuating arm 52 will be swung toward the left from the position shown in Fig. 2, in which movement the pawl 61 will ride off the retaining plate 64 and engage in the notch 59 immediately to the left of said retaining plate. Before the table 5 may be actuated by the arm 52, the retaining latch 65 must be disengaged from the table, and this is accomplished by the trip projection 73 of the arm 52 during the idle movement of the arm 52 before the pawl 61 engages in a notch 59. The interengaging faces 75 of the projection 73 and 72 of the trip member 68 being both inclined with respect to the longitudinal axis of the latch 65, the engagement of the projection 73 with the trip member 68 will force the latch 65 outwardly against the action of the spring 67 sufficiently to allow the projection 73 to pass the trip member 68 and to shift the latch 65 clear of the notch 60 in which it is engaged by the time that the pawl 61 has engaged in the notch 59 to shift the carrier. The angular movement of

the arm 52 is just sufficient during the upward movement of the head 2 of the press to move the table 5 through an angle equal to the angular distance between the pockets 7, so that upon successive actuations of the table, successive pockets 7 will be aligned with the discharge aperture 32 of the feed chute 9.

An angularly disposed yielding wiper 76 is secured to the discharge end 31 of the feed chute, and closely overlies the table 5 in front of the feed chute. The wiper 76 serves to brush off any additional blanks which might accidentally be discharged onto the table from the feed chute. To insure the proper positioning punch 77, which is formed to fit in the recess 13 of the blank, is secured to the head 2, and positioned to engage with a blank, in the pocket 7, which has been delivered therefrom to the feed chute 9 after the table has been actuated to shift the pocket containing the blank away from the feed chute.

Along the front of the supporting bed 1 there is secured a supporting block 78, the upper edge of which is substantially at the level of the top of the table 5, and this block forms a support for a reciprocating feed plate 79 which is adapted to carry a strip of packing material directly over the outer edge portion of the carrier table. The plate 79 is provided with a retaining flange 80 along its inner edge, and on the portion thereof overlying the table there is secured a stripper plate 81, which is undercut at 82 to provide a slot for the passage of a strip 83 of a suitable packing material, such as rubber. After each indexing movement, the carrier is stopped, with a pocket 7 containing one of the valve blanks, directly beneath an elongated slot 84 in the plates 79 and 81. The strip 83 of packing material lies between the plates 79 and 81, and extends across the slot 84. A punch 85 is rigidly secured to the head 2 of the press, and is positioned in axial alignment with a valve blank in the pocket 7 beneath the plate 79. The punch 85 is substantially the same in diameter as the recess 13 of the blank, so that as the punch 85 moves downwardly through the slot 84 it will press the rubber strip 83 against the upper end of the blank 11, and the upper cup-shaped end of the blank 11 will act as a die to sever a circular piece of packing which is forced into the recess 13 by the punch 85. To prevent adhesion between the severed packing and the lower end of the punch 85, the punch 85 has an axial passageway extending to its lower end, which communicates with a flexible conduit 85^a extending from the punch 85 to a suitable source of air under pressure. Air pressure is admitted to the punch at the end of the down stroke of the press head, and enables the punch to be separated from the packing which has been forced into the valve member without loosening the packing or dis-

lodging it from the valve member. The strip 83 of packing material is yieldingly held against the retaining flange 80 by a spring actuated pressure finger 86, and may be shifted by the operator, out of alignment with the slot 84, by means of a manually operable trip arm 87 which engages with the strip along the inner edge thereof.

To feed the strip of packing material along the supporting plate 79, the plate 79 is moved in one direction while the head 2 of the press is in elevated position, and in the opposite direction while the punch 85 is in engagement with the strip of packing material 83, the strip of packing being advanced during the movement of the supporting plate 79 by means of a bell crank lever 88 which is mounted on a transverse pivot 89 beneath the plate 79 beyond one end of the supporting block 78 and having one arm thereof in engagement with the plate 79. The other arm of the bell-crank 88 is connected to a vertical actuating rod 92 which has a lateral extension 93 at its lower end connected to said arm. The rod 92 is actuated in one direction by the reciprocating head 2 of the press as the head approaches its uppermost position and in the opposite direction as the head approaches its lowermost position, the rod 92 being slidably engaged by a bracket 94 secured to the head 2. A block 95 is adjustably secured to the vertical rod 92 by means of a taper pin 96, and is supported by a lever 97 which is mounted on a fixed support and carries a laterally projecting pin 98 against which the lower end of the block 95 rests, the lever 97 being provided with a spring 99 which serves to yieldingly take the weight of the block 95 and rod 92. The rod 92 is actuated by the bracket 94, only when the head approaches its uppermost position, and when the head approaches its lowermost position, the upper end of the rod 92 being provided at its upper end with a buffer spring 100, which is engaged by the bracket 94 in its upward movement, and with a buffer spring 101 resting upon the upper end of the block 95 which is engaged by the bracket 94 in its downward movement. The lever 97 has a serrated upper edge 102 which engages with a triangular pin 103 which projects from the inner side of the block 91 on the feed plate 79. As the press head 2 approaches its upper limit of movement, the bracket 94 engages the buffer spring 100 and lifts the rod 92, swinging the bell-crank 88 about its pivot, and moving the plate 79 to the left as shown in Fig. 1. As the plate 79 is moved by the bell-crank 88, the triangular pin 103 slides over the serrated edge 102 of the lever 97, and as the rod 92 is released by the downward movement of the head 2, the engagement of the triangular pin 103 with the serrated edge 102 of the lever 97 holds the feed plate 79 in the position to which it has been moved by the bell-crank 88. When the

head 2 approaches its lower limit of movement, the bracket 94 engages the buffer spring 101 and pushes the rod 92 downwardly. Since the block 95 is resting on the pin 98 carried by the lever 97, the downward movement of the rod 92 will cause the lever 97 to swing downwardly about its pivot, releasing the pin 103 from the lever 97. A return spring 104 is connected to the plate 79 and to the bed 1, and acts when the plate 79 is released to shift the plate 79 in a direction opposite that in which it had been previously moved by the bell-crank 88. During this return movement of the plate 79 the punch 85 is in engagement with the packing strip 83 and holds the strip against movement with the feeder plate. Thus, upon each reciprocation of the head 2, the strip 83 of packing material is moved forwardly a sufficient distance to bring an unperforated portion thereof to position over beneath the punch 85.

After the packing has been inserted into a valve member and the valve member with the packing therein has been shifted by the carrier to another position with respect to the head, the packing within the valve member is pierced by a punch 105 fixed to the head 2. The punch 105 is so positioned that it is in axial alignment with a valve member in one of the pockets 7, and is of a size to substantially fit into the bore 14 of the valve member, so that when the punch 105 engages the packing in a valve member, the bottom of the recess 13 of the valve member acts as a die, co-operating with the punch 105 to form a circular opening at the center of the packing of substantially the same diameter as the bore 14 of the valve member, this opening being formed to permit insertion of the valve pin into the valve member. The punch 105 also serves to discharge the valve members from the carrier table, the frictional engagement between the packing within the valve member and the punch 105 being sufficient to cause the valve member to be lifted by the punch out of the pocket 7. The punch 105 is provided with a follower 106 which is normally supported below the lower end of the punch, and is provided with an aperture through which the punch is forced when the follower 106 engages the top of the rotary table. The follower 106 is suspended from the head 2 by means of vertical bolts 107, which are secured at their lower ends to the follower 106, and are slidably mounted at their upper ends in the head 2. The bolts 107 have heads 108, slideable in counter-bores 109 in the head 2, and the follower 106 is yieldingly held in its lowermost position with respect to the head 2 by springs 110 surrounding the bolts 107 and interposed between the head 2 and the follower 106. As the head 2 moves downwardly, the follower 106 engages with the rotary table 5, directly over the pocket 7, which is

positioned beneath it, and upon continued movement of the head, the springs 110 are compressed and the punch 105 is forced through the aperture of the follower 106, and through the packing within the recess 13 of the valve member. Upon upward movement of the head, the frictional engagement of the packing with the punch 105 causes the valve member to move up with the punch, and also causes the follower 106 to be held above the lower end of the punch until the follower 106 engages with a stripper arm 111, carried by a post 112 on the bed 1, whereupon the follower is forced downwardly with respect to the punch until the lower end of the punch is within the follower, and the valve member is thus freed from the punch.

The actuating arm 52 has a lateral extension 113 adjacent the inner end thereof, upon which is pivoted a discharge chute 114, which is normally held in a position in which the rear end thereof abuts against the outer face of the projection 113 by a coil spring 115 connected at one end to the chute and at the other to the arm 52. During the movements of the arm 52, the chute 114 moves beneath the follower 106, and the movement of the chute 114 is so timed that it occupies a position beneath the follower at the instant when the follower engages the stripper arm 111, so that the valve members when freed from the punch 105 drop into the chute 114 and are discharged from the chute 114 into the chute 10 mounted on the bed 1.

When the actuating arm is in the position shown in Fig. 2, the head is in its lowermost position and the chute 114 is in engagement with the front side wall of the chute 10, in which position it is entirely in front of the follower 106. As the actuating arm 52 is swung to the left, as shown in Fig. 2, during upward movement of the head 2, the chute 114 remains in the position in which it is shown in Fig. 2, until the outer end of the projection 113 has been turned sufficiently with respect to the chute to engage the rear end wall thereof, whereupon the chute 114 moves with the actuating arm 52. By the time the chute 114 begins to move, the follower 106 and the punch 105 with the valve member sticking to the lower end thereof have been raised sufficiently to permit the chute to move beneath them. It sometimes happens that there is sufficient adhesion between the packing in the valve member and the under side of the follower 106 to cause the valve member to hang upon the under surface of the follower 106 after it has been freed from the punch 105. To insure the proper discharge of valve members under all conditions, the chute 114 is provided with a pivoted wiper arm 116, which is connected to the forward end of the rear side wall of the chute by a horizontal pivot 117, and has a projecting lug 118 which is below the pivot 117.

117 and engages with the stripper post 112 during rearward movement of the chute. The pivot 117 is provided with a spring washer 118, which causes a sufficient friction between the wiper arm and the side wall of the chute to normally hold the arm in any position to which it is moved. The engagement of the projection 119 with the post 112 causes the wiper arm 116 to be swung upwardly so that during the return movement of the arm 52, the wiper arm 116 engages the under face of the follower 106 and will brush a valve member sticking to the follower into the chute. The follower 106 has sufficient downward movement during the movement of the wiper arm 116 across its under face to move the wiper arm to its lowest position.

In the operation of the machine the rotary carrier table 5 is positioned, during each downward stroke of the head 2 of the press, with certain of the pockets 7 thereof directly beneath and in axial alignment with the various punches carried by the head. During the downward stroke the punch 35 forces a valve member from the discharge end of the chute 9 into the pocket directly beneath the aperture 32, the positioning punch 77 engages with a valve member which has been previously fed into a pocket, forces the valve member into firm engagement with the insert 39, the punch 85 at the same time engages the packing strip and co-acts with a valve member which has been previously fed and positioned in the pocket to sever a circular piece of packing material and force the same into the recess 13 of the valve member, and the punch 105 at the same time pierces the packing in a valve member which has previously been positioned in a pocket and had the packing inserted therein. Upon the up stroke of the head 2 of the press, the rotary table 5 is indexed by the actuating arm 52 which in its movement releases the table from its holding latch and shifts the table through an angular distance corresponding to the angular distance between the pockets 7, the valve member engaged by the punch 105 being at the same time lifted out of its pocket in the rotary carrier table 5 and discharged into the chute 114.

Having described my invention, I claim

1. In a machine for applying packing to cup-shaped valve members, a carrier having spaced pockets in which said valve members fit, a reciprocating head associated with the carrier, means for moving the carrier intermittently in timed relation to the stroke of the head, means for feeding valve members one at a time into the pockets, means for feeding a strip of packing material over a pocket of the carrier, a punch carried by the head and cooperating with a valve member to punch a washer from the strip and force the same into the valve members, and means car-

ried by the head for lifting the valve members from the pockets and discharging the same.

2. A machine for applying packing to cup-shaped valve members comprising a press having a bed and a reciprocating head movable toward and from the bed, a rotary table on the bed having pockets therein, adapted to hold valve members open end up, said pockets being regularly spaced circumferentially of the table, a plurality of punches carried by the head and spaced to cooperate with valve members in separate pockets of the table, means providing a direct actuating connection between the reciprocating head and the table for turning the table during the up-stroke of the head through an angle corresponding to the spacing of the pockets, and means for locking the table during the down stroke of the head with the pockets in axial alignment with the punches, and means for feeding a strip of packing material over a portion of the table beneath one of said punches.

3. A machine for applying packing to cup-shaped valve members comprising a press having a bed and a reciprocating head movable toward and from the bed, means on the bed for rigidly supporting a valve member open end up, a punch carried by the head, said punch being of a size to conform to the interior of the valve member and adapted to coact with the valve member to force a washer into the valve member, said punch having a passageway therethrough leading to its lower end, and means for supplying air under pressure to said punch to prevent the washer from sticking to the punch.

4. A machine for applying packing to cup-shaped valve members comprising a press having a bed and a head movable toward and from the bed, a carrier on the bed provided with a series of regularly spaced pockets, each adapted to support a valve member with the open end up, punches carried by the head and positioned to cooperate with spaced pockets of the carrier, means providing a direct actuating connection between the reciprocating head and the table for moving the carrier at intervals a distance corresponding to the spacing of the pockets, a feed chute having its discharge end over the carrier and in alignment with one of the punches, and means for supporting a strip of packing material beneath another of the punches.

5. A machine for applying packing to cup-shaped valve members comprising a press having a bed and a head movable toward and from the bed, a carrier on the bed provided with a series of regularly spaced pockets, each adapted to support a valve member with its open end up, carrier actuating means including a part connected to the reciprocating head and adapted to actuate the carrier during the up-stroke of the head, a punch carried by the

head and formed to fit the interior of a valve member, means for locking the carrier after each actuation thereof in a position in which a valve member in one of the pockets of the carrier is in axial alignment with said punch, means for supporting a strip of packing material immediately over a valve member on the carrier and beneath said punch, and means operated by the head for intermittently advancing said strip.

6. A machine for applying packing to cup-shaped valve members comprising a press having a bed and a reciprocating head movable toward and from the bed, a carrier mounted on the bed and provided with regularly spaced pockets each adapted to support a valve member open end up, means operated by the head for intermittently moving the carrier, means for feeding valve members to the pockets, means for locking the carrier during the intervals between actuations thereof, means for supporting a strip of packing material over a portion of the carrier, a punch carried by the head and adapted to cooperate with a valve member beneath the strip to sever a washer from the strip and force the same into the valve member, a second punch carried by said head and adapted to pierce a washer which has been inserted in the valve member and to lift the valve member from the carrier, and a stripper cooperating with the last mentioned punch to free the washer.

7. A machine for applying packing to cup-shaped valve members comprising a press having a bed and a reciprocating head movable toward and from the bed, a carrier on the bed having spaced pockets adapted to support valve members open end up, means actuated by the head for intermittently moving the carrier, a supply chute for valve members, means carried by the head for transferring valve members from the chute to successive pockets of the carrier, and means carried by the head for inserting washers into the valve members and for discharging the valve members.

8. In a machine for applying packing to cup-shaped valve members, a press having a bed and a reciprocating head movable toward and from the bed, a carrier on the bed provided with regularly spaced pockets each adapted to support a valve member open end up, a feed chute adapted to support a row of valve members open end up therein, said chute having a discharge end directly over the carrier and provided with yieldable means for retaining the foremost valve member, a reciprocating actuator for the carrier actuated by the head, means for connecting said actuator to the carrier during the up-stroke of the head, means for locking the carrier during the intervals between actuations thereof in a position such that a pocket is directly beneath the discharge end of the chute, and a feed punch carried by the head and adapted

to engage a valve member to transfer the same from the chute to the pocket of the carrier.

9. A machine for applying packing to cup-shaped valve members comprising a press having a bed and a reciprocating head movable toward and from the bed, a carrier on the bed provided with spaced pockets each adapted to support a valve member open end up, means for intermittently actuating the carrier in timed relation to the movement of the head, a feed chute, means carried by the head for delivering the valve members from the chute to the successive pockets of the carrier, means carried by the head for forcing washers into the valve members, means carried by the head for lifting the valve members out of the carrier, and means for discharging the valve members from the lifting means.

10. A machine for applying packing to cup-shaped members comprising a press having a bed and a reciprocating head movable toward and from the bed, a carrier on the bed provided with spaced pockets each adapted to support a valve member open end up, a punch carried by the head, actuating means for the carrier connected to the head and adapted to shift the carrier during the up-stroke of the head, means for locking the carrier during the intervals between actuations in positions in which the valve members are held in axial alignment with the punch, means for supporting a strip of packing material between the punch and the carrier, and means operated by the head for imparting a feed movement to the strip while the punch is out of engagement therewith.

11. A machine for applying packing to cup-shaped valve members comprising a press having a bed and a reciprocating head movable toward and from the bed, a carrier on the bed provided with regularly spaced pockets each adapted to support a valve member open end up, a feed chute adapted to support a row of valve members open end up therein, said chute having a discharge end directly over the carrier, and provided with yieldable means for retaining the foremost valve member, a reciprocating actuator for the carrier actuated by the head, means for connecting said actuator to the carrier during the up-stroke of the head, and means for locking the carrier during the intervals between actuations thereof, in a position such that a pocket is directly beneath the discharge end of the chute, a feed punch carried by the head adapted to transfer a valve member from the chute to a pocket of the carrier, a second punch carried by the head and positioned to co-act with a valve member in a pocket of the chute and formed to fit within a valve member, means for supporting a strip of packing material beneath said punch, a piercing punch positioned

to enter a washer in a valve member on the carrier and adapted to lift the valve member from the pocket, an oscillating discharge chute, means for moving said chute beneath the piercing punch during the up-stroke of the head, and means for stripping a valve member from the piercing punch to deliver the valve member into the discharge chute.

12. A machine for applying packing to cup-shaped valve members comprising a press having a bed and a reciprocating head movable toward and from the bed, a carrier on the bed provided with spaced pockets each adapted to support a valve member open end up, means for intermittently actuating the carrier in timed relation to the movement of the head, a feed chute, means carried by the head for delivering valve members from the chute to successive pockets of the carrier, means carried by the head for forcing washers into the valve members, means carried by the head for lifting valve members out of the carrier, an oscillating discharge chute, and means for moving said discharge chute beneath the lifter while the same is above the carrier and for disengaging the valve member from the lifter.

13. A machine for applying packing to cup-shaped valve members comprising a press having a bed and a reciprocating head movable toward and from the bed, a carrier on the bed having spaced valve member receiving pockets, a feed chute for supplying valve members to the pockets of the carrier, means operated by the head for vibrating said chute, and means operated by the head for inserting washers into said valve.

14. A machine for applying packing to cup-shaped valve members comprising a press having a bed and a reciprocating head movable toward and from the bed, a carrier on the bed provided with pockets adapted to support said valve members open end up, a punch carried by the head and formed to fit the interior of a valve member, means for actuating the carrier in timed relation to the movement of the head and for stopping the same in a position in which a valve member in a pocket is in axial alignment with a punch, means for supporting a strip of packing material over the carrier and beneath said punch, and means for intermittently advancing said strip.

15. A machine for applying packing to

cup-shaped valve members comprising a press having a bed and a reciprocating head movable toward and from the bed, a carrier on the bed provided with spaced pockets each adapted to support a valve member open end up, a punch carried by the head, actuating means for the carrier connected to the head and adapted to shift the carrier during the upstroke of the head, means for locking the carrier during the intervals between actuations in positions in which valve members are held in axial alignment with the punch, a reciprocating support adapted to hold a strip of packing material between the punch and valve members in the pocket of the carrier, means for shifting the support in one direction during the latter portion of the upstroke of the head and in the opposite direction during the latter portion of the down stroke.

16. In a machine for assembling valve members, a press having a bed and a head movable toward and from the bed, an intermittently moving carrier on the bed having spaced pockets each adapted to support a valve member, a supply hopper for valve members, a chute leading from the hopper to a point directly over the carrier and adapted to hold a row of valve members, means for delivering the valve members from the hopper to the chute with the open ends thereof uppermost, a vibrator plate extending along the top of the chute and means operated by the head for vibrating said plate, means operated by the head for delivering the valve members to the successive pockets of the carrier.

17. A machine for assembling valve members comprising a press having a bed and a head reciprocable toward and from the bed, an intermittently moving carrier on the bed having spaced pockets each adapted to support a valve member, means for delivering valve members open end up to the successive pockets, and means carried by the head and acting simultaneously upon valve members in separate pockets of the carrier, for inserting packing into one valve member and piercing the packing within another valve member.

In testimony whereof, I hereunto affix my signature.

EWALD F. TOBOLD.
